TABULATOR MECHANISM FOR TYPEWRITING-MACHINES.

1,362,071.

Specification of Letters Patent.

Patented Dec. 14, 1920.

Application filed January 23, 1917, Serial No. 143,990. Renewed March 21, 1919. Serial No. 283,688.

To all whom it may concern:

Be it known that I, NILS H. ANDERSON, a citizen of the United States, residing at Bridgeport, in the county of Fairfield and 5 State of Connecticut, have invented a new and useful Improvement in Tabulator Mechanism for Typewriting-Machines, of which the following is a specification.

In some classes of typewriting machines 10 when the tabulator key is depressed the feed rack is released from the feed and stop pawls, leaving the paper carriage free to be drawn across the frame by the spring barrel, and the tabulator frame is rocked so 15 that the stops which it carries will be swung into the path of and be engaged by a part projecting from the paper carriage for stopping the carriage at the desired place. As the paper carriage is comparatively 20 heavy and consequently has considerable momentum, particularly when drawn a substantial distance by the spring barrel, there is a heavy shock and much noise incident to the engagement of the stop on the carriage 25 with the stop on the tabulator frame.

The object of this invention is to provide means which are adapted to be attached to typewriting machines now in common use without materially altering the present construction, whereby the movement of the paper carriage can be controlled and the shock and noise incident to its stopping be eliminated.

For the purpose of illustrating the invention it is shown as applied to a typewriting machine of the "Underwood" make. Figure 1 of the accompanying drawings shows a rear elevation of such a machine with a shock absorbing and controlling 35 means which embodies this invention applied thereto. Fig. 2 is a plan showing the rear portion of the paper carriage and tabulator frame. Fig. 3 is a longitudinal section on larger scale of the shock absorbing 40 and noise eliminating support for one end of the tabulator frame. Fig. 4 is an enlarged cross section of a portion of the carriage frame and tabulator frame taken on the plane indicated by the dotted line 50 4-4 on Fig. 2.

In the machine shown the paper carriage 1 is drawn by the usual spring tension means 2 across the frame 3 in the direc-

tion indicated by the arrow on Fig. 1 with a step by step movement when the type keys 55 and space bar are operated in writing as is common in this class of machines. The tabulator frame of this type of machine has a pivot bar 4, a stop carrying rod 5 and a graduated rack bar 6, fastened at their 60 ends to plates 7. The tabulator stops 8 are adjustable along the stop rod and have fingers 9 that register with the graduations on the rack bar. The tabulator frame plate 7 at one end is pivotally mounted on 65 the end of a screw 10 which is turned through the upper end of the stationary machine frame into a socket in the lower end of the plate. At the opposite end the other tabulator frame plate 7 is pivotally mounted 70 at its lower end on the end of a plunger 11 which is movably held in a sleeve 12 that is screwed through the upper end of the stationary machine frame. On the outer end of this sleeve is a cup, tube or housing 75 13 which contains a plate or head 14 against which the end of the plunger abuts, and a rubber buffer 15 with a central opening 16. The outer end of the cup is closed by a screw cap 17. The cup 13, head 14 and 80 cap 17 form a casing inclosing and confining the buffer. The tabulator frame has a forwardly projecting arm 18 which is connected by a link 19 with the tabulator key lever 20 so that as the tabulator key lever 85 is operated when the machine is in use the tabulator frame is rocked forward in the manner common to this class of mechanisms. Extending downwardly from the rear of the paper carriage frame is a stop lug 21, 90 and when the tabulator frame is swung forward and the paper carriage feeds this stop lug 21 on the carriage is engaged by a stop 8 on the tabulator frame for stopping the carriage in the desired position. 95

The blow of the carriage stop lug against one of the tabulator stops is considerable owing to the momentum of the carriage, but in the construction illustrated the force of this blow is transmitted from the tabulator frame to the yielding plunger which forms the pivotal support of the tabulator frame at one end, and as this plunger is backed by the elastic cushion 15 in the cup 13 all shock is absorbed and the noise incident to the concussion is eliminated. 105

Stop 15 is made of rubber, and rubber is substantially incompressible. This body of rubber completely fills the bore of the cup, as does the head 14 of the stem 11, and, owing 5 to the incompressibility of the rubber, there is no noticeable endwise movement of the stem 11 or of the rack 7 at the concussion of the carriage, because the rubber is supported on all sides against yielding. The small central perforation of the rubber plug 15, at the point 16, may permit a very slight yielding of the plug, enough to avoid giving the rubber plug the effect of a rigid hard plug or stop; but, although the plug may, because 10 of its soft consistency, and because of the small central opening 16, yield a little, still this yielding is less in extent than a letter-feeding step of the carriage, and the recovery of the rubber plug to its normal condition would obviously, because of packing in the housing, be too sluggish and weak to enable it to throw the carriage back against the tension of the spring 2, which tension is always present.

25 It will thus be seen that a stop which is efficiently positive, for arresting or finally stopping the carriage without liability of excessive rebound, and which is noiseless, is conveniently and cheaply constructed by 30 placing the rubber stop in a cup or tube, which it fills, and setting against it a rigid head which is provided upon a stem which extends through the other end of the tube, the cup being closed by a screw, the whole device forming a unit for ready attachment to 35 a typewriting machine, to receive the impact of the carriage; the stem or shank being preferably inclosed in an extension of the cup which is threaded for attachment to the 40 typewriting machine; the thread giving a range of adjustment, so as to increase the life of the device, since adjustment may be effected to compensate for the variation in the size or movement of the rubber stop due 45 to use or age, while the whole device may be readily secured in its adjusted position. The screw 17 may be readily taken out to permit withdrawal of the plug 15 and replacement by a fresh plug, as required. While the 50 shank 11 may be used as a pivot of a stop-carrying rack still it may be otherwise used to permit the carriage to be arrested by the silent rubber stop 15.

In order to further relieve the shock of 55 the engagement of the carriage stop with the tabulator stop an adjustable brake is arranged on the carriage in position to engage with the tabulator frame when that frame is swung forward. This brake consists of a 60 spring arm 22 which has one end secured to the rear of the carriage frame and that on its other end has a friction pad 23 preferably made of leather. Movable on the carriage frame between the frame and the spring 65 brake arm is a wedge block 24 that can be

fastened in any desired position by the screw 25. By adjusting this wedge block along the carriage frame the pad on the end of the brake arm may be set in such position that it will frictionally bear against the rack bar 70 of the tabulator frame when that frame is swung forward, and thus control the momentum of the moving paper carriage and assist in relieving the shock and reducing the noise of the engagement of the carriage stop 75 with the tabulator stop.

The invention claimed is;

1. In a writing machine the combination of a supporting frame, a sleeve screwed into the supporting frame, a cup on the outer 80 end of said sleeve, a rubber buffer incased in said cup, a plunger movable in said sleeve and cushioned against said buffer, and a tabulator frame pivotally supported on the end of said plunger in such manner that the 85 shock of blows imparted to the tabulator frame is transmitted through said pivotal plunger and absorbed by said rubber buffer.

2. The combination with a typewriter carriage, a supporting frame therefor and a 90 tabulating mechanism comprising a stop on said carriage and a stop on said frame, of a noise-reducing connection between one of said stops and its supporting member, said connection comprising a buffer of material 95 having the resiliently deformable but relatively non-compressible properties of soft rubber, and a snugly fitting casing of rigid material inclosing and confining said buffer, said casing comprising a pair of relatively 100 movable buffer compression members connected respectively to said last-mentioned stop and its supporting member.

3. The combination with a typewriter carriage, a supporting frame therefor and a 105 tabulating mechanism comprising a stop on said carriage and a stop on said frame, of a noise-reducing connection between one of said stops and its supporting member, said connection comprising a buffer of material 110 having the resiliently deformable but relatively non-compressible properties of soft rubber, said buffer having a relatively small cavity therein, and a snugly fitting casing of rigid material inclosing and confining said 115 buffer, said casing comprising a pair of relatively movable buffer compression members connected respectively to said last-mentioned stop and its supporting member.

4. The combination with a typewriter 120 carriage, of a noise-reducing final stop therefor, comprising a rubber plug, a cup or tube which said rubber plug fills, a head movable in said tube or housing, a shank upon said head and extending through an end of said 125 housing for engagement with a part moved by the typewriter carriage, and means upon the other end of said tube for confining the plug compactly therein, said confining means in the form of a removable screw. 130

5. The combination with a typewriter carriage, of a noise-reducing final stop therefor, comprising a rubber plug, a cup or tube which said rubber plug fills, a head movable in said tube or housing, a shank upon said head and extending through an end of said housing for engagement with a part moved by the typewriter carriage, and means upon the other end of said tube for 10 confining the plug compactly therein, said housing having a threaded portion, whereby it may be attached to a part of the typewriting machine.

6. The combination with a typewriter carriage, of a noise-reducing final stop therefor, comprising a rubber plug, a cup or tube which said rubber plug fills, a head movable in said tube or housing, a shank upon said head and extending through an end of said housing for engagement with a part moved by the typewriter carriage, means upon the other end of said tube for confining the plug compactly therein, a support into which said housing is adjustably theaded, and 25 means to secure said housing where it is adjusted by its threads.

7. The combination with a typewriter car-

riage, of a noise-reducing final stop therefor, comprising a rubber plug, a cup or tube which said rubber plug fills, a head movable 30 in said tube or housing, a shank upon said head and extending through an end of said housing, and means upon the other end of said tube for confining the plug compactly therein, said shank having a pivotal portion, and the typewriter having a stop-carrying bar pivoted upon said pivotal portion.

8. The combination with a typewriter carriage, of a noise-reducing final stop therefor, comprising a rubber plug, a cup or tube which said rubber plug fills, a head movable in said tube or housing, a shank upon said head and extending through an end of said housing, means upon the other end of said 45 tube for confining the plug compactly therein, said shank having a pivotal portion, and the typewriter having a stop-carrying bar pivoted upon said pivotal portion, a support into which said housing is adjustably 50 threaded, and means to secure said housing where it is adjusted by its threads.

NILS H. ANDERSON.
